US00D745148S

(12) **United States Design Patent**
Gaynor et al.

(10) **Patent No.:** **US D745,148 S**
(45) **Date of Patent:** **** Dec. 8, 2015**

(54) **VAGINAL MANIPULATOR**

(71) Applicant: **Coloplast A/S**, Humlebaek (DK)

(72) Inventors: **Allen Gaynor**, Coon Rapids, MN (US);
Sarah J. Deitch, Minneapolis, MN (US);
Jeffrey Brian Taylor, Forest Lake, MN
(US); **Michael M. Witzmann**,
Shoreview, MN (US); **Ty Erickson**,
Idaho Falls, ID (US); **Thomas KraMer**,
Minneapolis, MN (US); **William
Atwood**, Coon Rapids, MN (US)

(73) Assignee: **Coloplast A/S**, Humlebaek (DK)

(**) Term: **14 Years**

(21) Appl. No.: **29/486,303**

(22) Filed: **Mar. 28, 2014**

(51) LOC (10) Cl. **24-02**

(52) U.S. Cl.

USPC **D24/141; D24/147**

(57) **CLAIM**

The ornamental design for a vaginal manipulator, as shown and described.

DESCRIPTION

FIG. 1 is an isometric view of a vaginal manipulator showing a head attached to a handle with door located on a bottom side of the head, the door being in a closed position.

FIG. 2 is a left side view of the vaginal manipulator illustrated in FIG. 1.

FIG. 3 is a right side view of the vaginal manipulator illustrated in FIG. 1.

FIG. 4 is a top view of the vaginal manipulator illustrated in FIG. 1.

FIG. 5 is a bottom view of the vaginal manipulator illustrated in FIG. 1.

FIG. 6 is a front view of the vaginal manipulator illustrated in FIG. 1.

FIG. 7 is a back view of the vaginal manipulator illustrated in FIG. 1; and,

FIG. 8 is an isometric view of the vaginal manipulator illustrated in FIG. 1 showing the door in an open position.

The broken lines shown in FIGS. 1-8 illustrate portions of the vaginal manipulator that form no part of the claimed design.

1 Claim, 6 Drawing Sheets
